CIGAR LIGHTER

John Sinko, Chicago, Ill.

Application January 16, 1935, Serial No. 2,087

20 Claims. (Cl. 219—32)

My invention relates to cigar lighters and has to do more particularly with electric lighters of the character used on automobiles having a removable lighter unit for lighting cigars, cigarettes, and the like.

One of the objects of my invention is to provide an improved and simplified device of the above character made up in units which may be readily assembled to produce a complete lighter.

10 Various features of my invention will be more particularly pointed out in the specification and appended claims.

For a better understanding of my invention reference is to be had to the accompanying drawing in which:

Fig. 1 is a side elevation of the complete device.
Fig. 2 is a top plan view of Fig. 1, but with the translucent cap of the lighter unit removed.

Fig. 3 is a cross sectional view along the line 20 3—3 of Fig. 2 showing the parts enlarged and with the translucent cap in place.

Fig. 4 is a side elevation of the spring actuated restoring unit removed from the lighter unit.

Fig. 5 is a top plan view of Fig. 4.
25 Fig. 6 is a disassembled view of the elements of the restoring unit of Fig. 4 with the parts shown in perspective.

Fig. 7 is a perspective view of the igniter element.

30 Fig. 8 is a bottom view of Fig. 7; and

Fig. 9 is a disassembled view of the parts of the base or holder shown in perspective.

In general it might be stated that the device is of the wireless type in which the lighter unit or head is removably held on the base or holder and adapted to be bodily pressed inwardly to close the circuit for the igniter unit, and when the hand pressure is relieved the lighter unit restores to its normal position opening the lighter circuit, and the unit may then be removed from the base for lighting a cigar or the like.

Referring now more in detail to the preferred construction employed, I provide a tubular body A of a heat resisting insulating material, with a central hub 1 disposed intermediate the ends of the body A and having radially extending arms 2 with the hub and arms preferably cast with the tubular portion A to form an integral structure. The arm structure thus provides light passages as 3, through which the light from the glowing igniter element may pass upwardly through the tube A to be observed through the translucent window 4 held in a metal ring 5 removably pressed into the upper or outer end of the body A and frictionally held therein.

This central hub 1 is adapted to support the igniting element shown in Figs. 7 and 8 and the spring actuated restoring unit of Figs. 4 and 5 as indicated in Fig. 3, the restoring unit of Fig. 4 also serving as a holding ring adapted to frictionally engage a supporting base. This restoring unit is preferably made up as a self-contained unit including an inner ring or sleeve 6 having a flanged end 7 and a plurality of friction sections 8, preferably four in number and formed by cutting out a pair of slots 9 for each section 8 so as to permit the sections 8 to yield as indicated in Fig. 3. A small depressed portion 10 serves to effect a more positive electrical contact with the base. A supporting ring 11 fits inside 15 the ring 6, the flange 12 engaging the inwardly turned flange 13 of the other ring to prevent separation of the parts from the action of spring 14. An upper abutment for the spring 14 is provided by the plate 15 which is secured to the inner ring 20 11 by a pair of ears 16 which fold down underneath the central hub 17 of the ring 11 as indicated by the dotted lines in Fig. 5, and also as shown in Fig. 3. The other pair of ears 18 are adapted to be bent upwardly so as to engage the 25 central hub 1 of the body A so as to properly align the openings 19—20 with the light passages or openings 3 in the body A so that the light may pass directly up to the translucent cap. In assembling the restoring unit of Figs. 4 and 5, the 30 spring 14 is placed around the holding ring 6 and the inner ring 11 slipped up inside of the holding ring 6 after which the top flange or abutting plate 15 is placed over the top of the inner ring 11 and the ears 16 folded underneath the central 35 hub 17 of the inner ring with the two rings 6 and 11 holding the spring 14 under compression. Thus with the restoring unit assembled as shown in Figs. 4 and 5, and the use of the flat restoring spring 14, the tubular wall portion of this restoring unit is comparatively thin and thus takes less space in the lighter head.

The igniting element as shown in Figs. 7 and 8 includes a cup-like holder 23 with light passages 24 in its upper face and having a supporting stud 45 25 insulatingly clamped or attached to the cup 23 by a nut 26 with interposed insulating washers 27—28 preferably of mica, and with the stud 25 passing through a central opening in the cup 23 which is large enough to keep the stud 25 from 50 making electrical contact with the cup 23 as indicated in Fig. 3. A spiral lighter ribbon 29 is placed within the cup 23, being connected at its inner end in the slotted end of the stud 25 and with its outer end electrically connected with the 55

outer rim of the cup 23 preferably by being welded thereto. Thus I provide a self-contained igniter element which may be secured to the hub 1 of the body A by the fastening stud 25 which also passes through the central opening of the restoring unit 5 of Figs. 4 and 5 so as to clamp this restoring unit against the central hub 1.

In assembling the body A, igniter unit, and restoring unit, the restoring unit is first pressed up 10 into the body so that the light openings 19-20 and 3 register, after which the fastening stud 10 of the igniter unit is passed up through the central openings and the parts clamped together by nut 30.

15 Referring now to the base or holder, I provide a clamp or bracket formed up of sheet metal having its front leg 32 provided with a boss 33 formed up out of the metal with a slot 34 extending from the center of the boss to the point 20 35 in the clamp to carry a conductor away from the center terminal. This boss 33 acts to receive the cupped end 36 of a holding tube or sleeve 37 which is adapted to be inserted into the holding ring 6 of the lighter unit.

25 A cupped escutcheon 38 has its central annular flange 39 clamped between the base of the sleeve 37 and the leg 32 of the clamp. A contact cup 40, adapted to make contact with the rim 23 of the igniting unit cup is insulatingly secured to the base by means of a rivet 41 passing through 30 the hole 42 of the clamp, which hole is large enough to clear the shank of the rivet so as to prevent electrical contact between the rivet and clamp. An insulating disc 43 of mica is interposed between the contact cup 40 and cup 36 of 35 the holding sleeve and an insulating washer 44 interposed between the cupped portion 33 of the clamp and the washer 45 to insulate the contact cup 40 and stud 41 from the base. A short conductor 46 is preferably permanently attached to 40 the base by having its end clamped against the stud 41 so as to provide a terminal for connecting the ungrounded terminal of a battery to the device.

45 In assembling the base, the cupped end of the holding ring 37 is placed against the base, after which the cup 40, washers 43-44, conductor terminal 46 and washer 45 are all clamped together by the rivet 41.

50 In the operation of the device, and assuming the lighter unit A is in place on the base as shown in Fig. 3, with one terminal of the battery connected to conductor 46 and the other grounded to the frame of the car and thus to the clamp 32. 55 When pressure is applied against the outer end of A it is moved downwardly against the tension of spring 14 as the parts of the restoring unit of Fig. 4 telescope. This downward pressure brings the rim of the igniter element cup 23 in contact 60 with the rim of the base cup 40, thereby closing a circuit through the heater element 29 extending from battery terminal 46, stud 41, cup 40, cup 23, through the heating element 29, then through the central stud 25 to the parts of the restoring units 65 (Fig. 4), the base holding sleeve 37, to the grounded frame through the clamp 32.

As the lighting element comes to incandescence the light rays extend upwardly through the light passage 20-19 of the restoring unit and through 70 the light passages 3 of the supporting spider, and up through the cap 4. By now relieving the pressure on the lighter unit A, spring 14 forces the unit A upwardly to interrupt the circuit through the lighter element and the unit A may 75 then be withdrawn from the base for use.

To replace the igniting element, the top cap 4 is removed, and the nut 30 removed, whereupon the lighter element may be withdrawn from the device and replaced by a new one.

I claim:

1. In a cigar lighter, a removable lighter unit comprising an integral tubular body of insulating material, a hub permanently supported by radially extending arms inside said body intermediate the ends, an igniting element having a stud extending through said hub for removably supporting the element in the hub in one end of the body, and a unit supporting ring inside the body surrounding the element and clamped between said element and hub. 15

2. In a cigar lighter, a removable lighter unit comprising an integral tubular body of insulating material, a hub permanently supported by radially extending arms inside said body intermediate the ends, an igniting element having a stud extending through said hub for removably supporting the element in the hub in one end of the body, a unit supporting ring inside the body surrounding the element and clamped between said element and hub, said supporting ring comprising a pair of telescopically sliding collars and a spring surrounding one of said collars with means whereby said collars are held normally telescopically extended by said spring, and a base adapted to receive one of the collars as a removable support for the unit. 20

3. In a cigar lighter, a removable lighter unit comprising an integral tubular body of insulating material, a hub permanently supported by radially extending arms inside said body intermediate its ends, an igniting element having a stud extending through said hub for removably supporting the element in the hub in one end of the body, a unit supporting ring inside the body surrounding the element and clamped between said element and 35 hub, said supporting ring comprising a pair of telescopically sliding collars and a spring surrounding one of said collars with means whereby said collars are held normally telescopically extended by said spring, a base adapted to receive one of the collars as a removable support for the unit, and a contact element in the base adapted to be engaged by the igniting element to complete a circuit through the element by hand pressure on the unit against tension of the spring. 40

4. In a cigar lighter, a removable lighter unit comprising a tubular body of insulating material, having an integral inner hub supported intermediate the body ends with light conducting openings surrounding the hub, an igniting element supported inside one end of the body by said hub and formed to pass light rays therefrom, through said openings toward the other end of the body, a translucent cap for said latter end of the body, and means within the igniting end of the body for removably supporting the body on a base. 55

5. In a cigar lighter, a removable lighter unit comprising a cast integral tubular body of insulating material, a fastening hub of like insulating material including radially extending supporting arms, said hub being held by said arms and positioned inside said body intermediate its ends, an igniting element having a stud extending through said hub for supporting said element in one end 60 of the body, and a unit supporting ring inside the body at the element and clamped between the igniting element and hub. 70

6. In a cigar lighter, a removable lighter unit comprising a cast integral tubular body of insu- 75

- lating material, a fastening hub of like insulating material including radially extending supporting arms, said hub being held by said arms and positioned inside said body intermediate its ends, an 5 igniting element having a stud extending through said hub for supporting said element in one end of the body, and a unit supporting ring inside the body surrounding the igniting element and attached to the fastening hub.
10. 7. In a cigar lighter, a spring actuated restoring and holding unit for insertion in a removable lighter unit comprising an outer tubular holding sleeve having an outwardly extending annular flange at one end and an inwardly extending annular flange at the other end, an inner tubular sleeve telescopically slidably positioned in the outer sleeve and having an outwardly extending annular flange inside the outer sleeve for engaging the inner flange of the outer sleeve to limit 20 the relative movement of the sleeves, a cap plate secured to the outer end of the inner sleeve to provide an outwardly extending flange, and a spring surrounding the outer sleeve between the cap plate flange and outer flange of the outer sleeve 25 tending to yieldingly hold the sleeves extended.
8. A spring actuated holding unit as called for in claim 7 in which the outer or holding sleeve has a plurality of yielding strips formed in its 30 wall by cutting out paired slots in the wall and each strip having a small depression in its outer face to form a slightly inwardly extending contact making tip.
9. In a cigar lighter, a base for removably supporting a lighter unit, said base comprising a sheet metal U-shaped clamp, one leg of said clamp having a cupped portion formed therefrom, a cup-like unit supporting tube having a cup formed bottom to snugly fit the clamp cupped 35 portion, an escutcheon surrounding the supporting tube and held between the tube bottom and the clamp leg around the cupped portion, a contact element inside the supporting tube, and means including a stud extending through all said 40 elements for clamping said elements together and insulating the contact element from the supporting tube and clamp.
10. A device as called for in claim 9 in which a slot is provided in said leg of the clamp extending 45 from the wall of the cupped portion with a conductor secured to the stud inside the cupped portion and passing along the slot to a point outside the clamp.
11. In a cigar lighter, a removable lighter unit 50 comprising a tubular body, a hub permanently supported by radially extending arms inside said body intermediate the ends, an igniting element having a stud extending through said hub for removably supporting the element in the hub in 55 one end of the body, and a unit supporting ring surrounding the element and clamped between said element and hub.
12. In a cigar lighter, a removable lighter unit 60 comprising a tubular body, a hub permanently supported by radially extending arms inside said body intermediate the ends, an igniting element having a stud extending through said hub for removably supporting the element in the hub in one end of the body, and a unit supporting ring 65 surrounding the element and interlocking therewith to prevent separation of said ring from said element.
13. In a cigar lighter, a removable lighter unit 70 comprising a tubular body having a permanently secured inner hub supported intermediate the
- body ends with light conducting openings surrounding the hub, an igniting element supported inside one end of the body by said hub and formed to pass light rays therefrom, through said openings toward the other end of the body, a 5 translucent cap for said latter end of the body, and means associated with the igniting end of the body for removably supporting the body on a base.
14. In a cigar lighter, a removable lighter unit 10 comprising a cast tubular body having a permanently secured inner transverse wall positioned intermediate the ends of the body providing a chamber in each end of said body, said wall having light conducting passages there- 15 through, an igniter element positioned in one end chamber of the body and removably secured to said wall, said element having an open back registering with the light passages in the wall to conduct light from the element to the other end 20 chamber, a translucent cap for said latter chamber, and a frictional holding device yieldingly mounted for bodily movement with respect to said cap within the first chamber and surrounding the igniter element, said holding device forming a contact for the unit adapted to hold said 25 unit on a stationary base member.
15. In a cigar lighter, a spring actuated restoring and holding unit for insertion in a removable lighter unit comprising an outer tubular holding sleeve having an outwardly extending flange at one end and an inwardly extending flange at the other end, an inner tubular sleeve telescopically slidably positioned in the outer sleeve and having an outwardly extending flange 30 inside the outer sleeve for engaging the inner flange of the outer sleeve to limit the relative movement of the sleeves, a cap plate secured to the outer end of the inner sleeve to provide an outwardly extending flange, and a spring surrounding the outer sleeve between the cap plate 35 flange and outer flange of the outer sleeve tending to yieldingly hold the sleeves extended.
16. In a cigar lighter, a base for removably supporting a lighter unit, said base comprising a sheet metal clamp having a cupped portion 40 formed therefrom, a cup-like unit supporting tube having a cup formed bottom to snugly fit the clamp cupped portion, and means including a stud extending through all said elements for 45 clamping said elements together and insulating the contact element from the supporting tube and clamp.
17. In a cigar lighter, a removable lighter unit 50 comprising a cast tubular body having a permanently secured inner transverse wall positioned intermediate the ends of the body, said wall having light conducting passages there- 55 through, an igniter element positioned in one end chamber of the body and removably secured to said wall by a screw passing through said wall and connected to said igniter element, said element having an open back registering with the light passages in the wall to conduct light from 60 the element to the other end chamber, a translucent cap for said latter chamber, and a holding device associated with the first chamber surrounding the igniter element.
18. A cigar lighter head adapted to be remov- 65 ably mounted on a terminal base having a fixed terminal sleeve, comprising: a tubular body member; an igniting member secured to the inner portion of said body member; and means for removably supporting said body member on said 70
- 75

base comprising an electrical contact sleeve telescopically mounted within said body and adapted to engage frictionally the outside of said terminal sleeve, and a spring substantially coextensive in length with the contact sleeve and disposed between said contact sleeve and body side-wall so as to urge the contact sleeve forwardly.

19. A cigar lighter head adapted to be removably mounted on a terminal base having a fixed terminal sleeve, comprising: a tubular body member; an igniting member secured to the inner portion of said body member; and means for removably supporting said body member on said base member comprising an electrical contact sleeve provided at its outer end with a flange extending towards the wall of the body member telescopically mounted within said body and adapted to engage frictionally the outside of said terminal sleeve, and a spring disposed between said contact sleeve and body side-wall so as to bear against said flange and be concealed thereby.

20. A cigar lighter head, adapted to be removably mounted on a base providing a fixed electrical terminal in the form of a conducting sleeve and a second fixed terminal insulated therefrom, comprising: a hollow body member; a metallic supporting plate mounted in said body member; an igniting coil mounted on said supporting plate with one end electrically connected thereto and the other end adapted to make electrical contact with the second mentioned base terminal; 10 a contact sleeve telescopically mounted within said body and adapted to engage frictionally the outside of said base sleeve; and a coiled compression spring substantially coextensive in length with the contact sleeve and disposed between the 15 side-wall of the body member and contact sleeve so as to urge said contact sleeve forwardly and maintain its electrical connection with said supporting plate.

JOHN SINKO. 20
